(57) **CLAIM**

We claim the ornamental design for a radio remote control unit, as shown and described.

DESCRIPTION

FIG. 1 is a perspective view when viewed front and left-side top;

FIG. 2 is a front view;

FIG. 3 is a rear view;

FIG. 4 is a plane view;

FIG. 5 is a bottom view;

FIG. 6 is a right-side view;

FIG. 7 is a left-side view; and,

FIG. 8 is a view showing the article in use, in which a light-emitting part in the center of the front panel lights up in time with power activation.

This article is a radio remote control unit which sends radio waves and carries out the remote control of the body (model) to be controlled.
